PHYSIOTHERAPY CABINET

Rudolf Emil Lind, Milwaukee, Wis.

Application November 4, 1944, Serial No. 561,902

8 Claims. (Cl. 128—373)

1

This invention relates to improvements in physiotherapy apparatus.

It is a primary object of the invention to provide novel and improved means whereby a patient may be treated with infra-red rays, or the like, without being subjected to fever conditions and without being weakened or enervated.

More specifically, it is my purpose to provide a closed cabinet in which a patient may be wholly confined during treatment, but in which temperatures will automatically equalize at a predetermined value to keep the patient from an oppressive sense of being overheated, I accomplish the protection of the patient and achieve comfort, despite the penetrating effect of the infra-red rays to which he is subjected in the course of treatment, first, by providing for gravity ventilation of the cabinet at a stabilized rate predetermined with reference to the amount of sensible heat generated by the lamps and the patient's body, thereby maintaining cooling air in circulation about the patient, and, secondly, by preventing the withdrawal of blood from the patient's head or from his feet and ankles.

In this latter connection, it is very important that heat be applied to the ankles and the upper surface of the feet during treatment, and the invention is concerned with means for accomplishing this objective.

It is a further very important object of the invention to provide a physiotherapy cabinet in which a patient may be fully enclosed for treatment and into which, notwithstanding the small and compact form of the cabinet, the patient may readily enter and emerge without assistance.

My objective with regard to the comfort and facility of entering and leaving the cabinet has to do with a specific arrangement of the seat with reference to the floor, the door, and a platform on which the seat is mounted.

Other objects will be apparent to those skilled in the art upon analysis of the following disclosure of the invention.

In the drawings:

Fig. 1 shows a cabinet embodying my invention in a view taken in section on the line 1—1 of Fig. 2.

Fig. 2 is a view of the improved cabinet as it appears partially in plan and partially broken away in horizontal section showing the interior of the cabinet.

Fig. 3 is a fragmentary detail view taken in section on the line 3—3 of Fig. 2.

Like parts are designated with the same reference characters throughout the several views.

2

My cabinet 4 is just sufficiently large to wholly receive a seated patient. In its front wall 5 there is a door opening 6 fitted with a door 7 hinged to the wall at 8 and provided with interior and exterior handrails 9, 10.

The cabinet is provided with a floor at 15. Above the floor 15 is a platform at 16 substantially coextensive with the interior of the cabinet except where it is deeply notched at 17 directly in front of the door, at which point the floor 15 is exposed. The exposed area of the floor 15 is separated by a partition 18 from a chamber 19 between the platform 16 and the floor 15 at the rear and sides of the cabinet. Ports 20 in the side wall 21 of the cabinet admit exterior air to the chamber 19. A register 22 in the platform 16 is provided with a manually operable valve 23 for regulating the flow of exterior air from the chamber 19 into that portion of the cabinet occupied by the patient.

Extending from front to rear of the cabinet on the platform 16, on either side of the doorway, are channels 24 comprising rails for a wheeled seat 25. From a position well back in the cabinet, as shown in Figs. 1 and 2, the seat may move forwardly upon its rails 24 to a position immediately adjacent the doorway. Consequently, with the seat drawn forwardly, the patient may seat himself thereon and, by the thrust of his feet, he may move the seat back into the cabinet, carrying his body thereon.

The cabinet space occupied by the patient is vented upwardly through the ports provided at 27 (Fig. 2). Thus gravity circulation may occur, subject to the control of the valve or damper 23, from the intake ports 20 through the chamber 19 and register 22 and outwardly through the vents at 27.

Sockets, preferably of a duplex type, are provided at upper and lower levels at 28 about the side walls and back wall of the cabinet for the treatment of a patient occupying the seat 25. Additional sockets at 29 are supported on the sides and back portions of the partition 18 which extends angularly about the recess provided by the notch 17 of platform 16. The platform overhangs the sockets 29 sufficiently for the protection of the bulbs therein, and the margin of the platform about the notch 17 prevents the patient's extremities from directly contacting such bulbs. It will be understood that when the patient is in the cabinet, seated upon the seat at 25, his feet will extend through the notch 17 for support directly on the floor 15 below the level of the platform 16.

The bulbs used in the several sockets, as above described, will preferably be of the type which emanate infra-red rays in substantial quantity. A certain amount of light is also developed by such bulbs, but it is a feature of the present invention to relieve the patient of undesirable sensible overheating by the controlled circulation of air. Even without the use of the damper or valve 23, the dimensions of the ports 20, 21 may be, and preferably are, so determined that the temperature in the interior of the cabinet will not rise more than 30° above the temperature of the room in which the cabinet is placed. With the room at 75°, the interior of the cabinet should stabilize itself at approximately 105°. The flow of air is proportioned to the temperature differential between the cabinet and the room and any excess of temperature within the cabinet beyond the predetermined 30° differential will accelerate the flow of air, while any decrease of cabinet temperatures below the 30° differential will cause a diminution of the gravity circulation of air.

In physiotherapy cabinets of the type heretofore generally used, the cabinet has usually been apertured for the patient's neck, and the patient's head has been left exposed. The heating of the body and the stimulation of bodily circulation by the infra-red lamps tends to draw the blood away from the head, with the result that the patient becomes faint. Also, despite attempts to heat the feet from below, there has been a tendency to withdraw blood from the feet so that the feet remain relatively unheated. Both of these difficulties are remedied in the present device, in which the circulation of air over the patient's body tends to eliminate any feeling of undue warmth and actually to maintain at a comparatively low value the temperature of the skin. Thus, notwithstanding the penetrating effects of the infra-red rays of the lamps, the patient does not feel uncomfortably warm and is not uncomfortably warm in fact.

By means of the lamps in sockets 29, which direct infra-red rays upon the blood vessels which are close to the skin in the upper surfaces of the feet and in the ankles of the patient, circulation is maintained at these points much more effectively than would be possible in any attempt to heat the feet through the floor. Thus the fatigue producing effects of the ordinary physiotherapy treatment is largely avoided and a patient may be treated in this cabinet with an increase rather than a decrease of energy and without having to feel discomfort at any time. Notwithstanding these advantages, the cabinet is small enough to be acceptable in the average home. Despite its small size, the sliding seat makes it possible for the patient to be seated at the door and to rise from his seat at the door, thus facilitating entry and egress without assistance.

I claim:

1. A physiotherapy device comprising a cabinet having a door and a floor, in combination with a platform spaced above the floor providing seating means and deeply notched at the door to provide a recess in which the floor is exposed to receive the patient's feet, the interior of the cabinet providing lamps for treatment, some of said lamps being located about said recess below platform level in a position for treating a patient's ankles and the upper surfaces of his feet.

2. A physiotherapy cabinet provided with a door opening and a door, a substantially horizontal platform within the cabinet notched to provide adjacent the door a recess for the feet of a

patient undergoing treatment, a partition extending about said recess between the platform and the bottom of the cabinet, guide rails on the platform at either side of the door opening extending from the door opening to the interior of the cabinet, a seat mounted transversely between said rails and provided with wheels operable along said rails for guiding the reciprocation of said seat to and from the door opening, said seat being wholly within the cabinet and movable to carry to and from the door opening the body of a patient seated thereon and whose feet are accommodated in said recess, and a door fitted to said opening.

15. 3. The cabinet defined in claim 2, in which said partition is spaced inwardly from the margin of the platform at said recess to provide a channel opening to the recess, and radiant means disposed in said channel and overhanging by said platform.

20. 4. The device of claim 2, in which said cabinet has an air inlet below said platform, and an air outlet adjacent its top, said platform having a register provided with a manually operable valve whereby air flow through the portion of the cabinet occupied by a patient on said seat is gravity induced subject to the control of said valve.

25. 5. The device of claim 2, in which said cabinet has an air inlet below said platform, and an air outlet adjacent its top, said platform having a register provided with a manually operable valve whereby air flow through the portion of the cabinet occupied by a patient on said seat is gravity induced subject to the control of said valve, the capacity of the inlet and outlet being calculated

30. 35. to maintain, subject to the control of said valve, a predetermined differential of temperature between the air within the cabinet and the exterior air.

40. 6. The device of claim 2, in which said platform overhangs said partition about said recess, and said cabinet is provided with lamps beneath the overhanging platform in a position to illuminate a patient's feet disposed within said recess, said cabinet having an air inlet opening into said cabinet behind said partition and beneath said platform, and having an air outlet opening from an upper portion of the cabinet, said platform having a register affording communication and air flow between the inlet and outlet.

45. 7. A physiotherapy cabinet having at its front a doorway and a door movable between open and closed positions, guide means extending into the cabinet at each side of the doorway, said cabinet being provided with a floor adjacent to the doorway and below the level of the guide means and adapted to receive a patient's feet, and a seat

50. 55. wholly supported on said guide means within the cabinet and extending transversely between the guide means and reciprocable in the cabinet to and from the doorway, said seat being adapted, when adjacent the doorway, to receive a patient seated backward thereon and to carry the body of the seated patient into the cabinet while the patient's feet rest on said floor in a position which does not interfere with the patient's manipulation of said door.

60. 65. 8. A physiotherapy cabinet having a doorway and a floor within the doorway, a platform spaced above the floor and deeply notched at the doorway to provide a recess in which the floor is exposed to receive a patient's feet, guide means extending along the platform into the cabinet at each side of the doorway and a seat extending transversely between the guide means and wholly supported thereon within the cabinet for recipro-

cation in the cabinet to and from the doorway, said seat being adapted to receive a patient seated backward thereon and to carry the body of the seated patient into the cabinet away from the doorway while the patient's feet rest on said floor. 5
